CLOSURE MEANS

Abram W. Wheaton, Maplewood, N. J., assignor
to A. W. Wheaton Brass Works, Newark, N. J.,
a corporation of New Jersey

Application March 23, 1938, Serial No. 197,625

4 Claims. (Cl. 220—39)

This invention relates to closures and more particularly to closures for sewers, meters, pipe lines, fluid transportation and storage tanks and for like units having an opening which must be opened and closed. In one of its more specific aspects the invention is directed to a detachable closure for a fill box connected to an underground storage tank used for the storing of fluids, such as gasoline, oil or other petroleum products.

One of the objects of the invention is to provide a closure and cooperative actuating tool which assures closing and proper sealing of a previously opened unit by the operator subsequent to use thereof and prior to leaving the same after such use.

Another object of the invention is to maintain the closure and detachable closure operating tool coupled together after the closure has been detached from a unit to open the latter for use, so that the tool cannot be detached and carried away until after the closure is replaced in closed relation to the unit.

These and other objects of the invention will be readily apparent from the following description and appended drawing, wherein:

Figure 1 is a top plan view of a fill box and a closure therefor embodying my invention. This figure illustrates the position of the head of a closure tool immediately after the tool head is inserted into the closure or immediately before its removal from the closure.

Figure 2 is a cross sectional view taken on line 2—2 of Figure 1 and in the direction of the arrows.

Figure 3 is a top plan view of Figure 1, but with the cover plate of the novel closure removed.

Figure 4 is a top plan view of a fill box and the novel closure therefor. This figure illustrates the position of the head of a closure tool when it is locked to the closure.

Figure 5 is a cross sectional view taken on line 5—5 of Figure 4 and in the direction of the arrows.

Figure 6 is a top plan view of Figure 4, but with the cover plate of the novel closure removed.

Although my novel closure may be used as a closure for a number of different units, such as pipe lines, transportation tanks, meters and the like, I shall, for the purpose of explaining the invention, describe the same as applied to close a fill box to seal the same and prevent the entrance of extraneous matter into the fill box and the escape of fumes from a storage tank coupled thereto.

Referring to the drawing, the reference char-

acter 10 indicates a filling pipe extending downwardly from the ground level to an underground storage tank (not shown). The upper end of the pipe 10 is threaded and makes a threaded connection with the threaded lower end of the cylindrical portion 11 of a fill box. The fill box comprises the cylinder 11 which is internally threaded at both its upper and lower portions, and which is provided with an annular enlarged top end portion 12 integral therewith. Said end portion is provided with a countersunk seat 13 concentric to the bore of the cylinder 11, the same being adapted to seat a closure device.

According to my invention, I provide a closure adapted to cooperate with the fill box to adequately seal the same. The specific closure illustrated comprises a plug or closure member 20, which as shown, is a male member having external threads thereon adapted to make a threaded connection with the threaded upper end of cylinder 11 of the fill box.

The threaded plug or closure member 20 has an annular flange 21 integral therewith. The lower face of the flange 21 extends outwardly from the threaded surface of the plug 20 and has an annular gasket 22 at its under side. The gasket 22 may be composed of rubber or other material having the desired sealing characteristics inherent in rubber and such other materials as leather, fiber and the like. The top end of the plug or closure member is provided with a circular recess 21' which is internally coarsely threaded, and a correspondingly coarsely threaded socket plate 23 makes a threaded connection with the interiorly threaded recess 21'. A stop pin 24 is fixedly secured to the annular flange 21 to project into the recess 21'. The socket plate 23 has an indented arcuate marginal opening 25 into which the stop pin 24 extends. This opening extends only a short distance along the circumference and along the complete depth or thickness of the plate 23. The plate 23 has a non-circular central socket opening 26 preferably of substantially rectangular shape adapted to accommodate the correspondingly shaped head 30 of a tool or wrench 31, and I prefer that the socket opening have one axis longer than another of its axes. The head 30 of the tool 31 is provided with a shank 32 and handle 33. A cover plate 27 is secured to the flange 21 by stud bolts or screws 28. The lower face of the cover plate 27, when the plate is secured to flange 21, is so located that the distance between the bottom of the recess 21' and the lower face of

plate 27 is greater than the thickness of the socket plate 23.

The cover plate 27 has an opening 28 of the same size and shape as the socket opening 26 and these openings are in register with each other when the plate 23 is in its lowermost position determined by stop pin 24 or the bottom of the recess 21'. The upper longitudinal edges of the cover plate, defining opening 28, are chamfered at 29 as shown. The chamfers 29 extend upwardly outward from the sides of said opening to the top of the cover plate. The longitudinal edges of each chamfer 29 form a V and the apices of the V shaped chamfers are at opposite ends of the opening.

The lower longitudinal edges of the tool head 30 are chamfered at 29'. The chamfers extend inwardly downward from the sides thereof to the bottom. The longitudinal edges of each chamfer form a V and the apices of the V shaped chamfer are at opposite ends of the tool head. With the tool head 30 and the sides of the opening 28 chamfered as described, when the tool head 30 is inserted in the opening and rotated, the tool head will slide out of the opening 28 unless the tool is lowered into the socket opening 26, thus assuring that the closure device cannot be operated unless the tool head is fully inserted therein and interlocked therewith.

In operation, assuming that the closure is tightly connected to the fill box unit, as shown in Figure 1, and it is desired to detach the closure from the fill box, the operator inserts the tool head 30 through the opening 28 and into the socket opening 26. At this moment, the elements of the closure and the fill box are in the relative positions shown in Figures 1, 2 and 3. After inserting the head 30 of the tool into socket opening 26, the operator rotates the tool in one direction to unscrew or detach the plug or closure member 20 from the female coupling of the fill box.

In the course of initially rotating the tool to uncouple the plug or closure member from the fill box, the socket plate 23 first rotates and rides upwardly on its threaded connection to the walls of the recess 21' until the upper thread of the plate 23 is jammed between the upper thread on the flange 21 and the lower face of the cover plate 27 to frictionally lock the plate 23 in its upper position, so that the openings 26 and 28 are relatively displaced and no longer in register, but the former is now disposed at an angle to the other, with a portion thereof located subjacent the cover 27. When the plate 23 reaches this position, one extreme of the opening 25 is spaced just a small distance from the stop pin 24. This movement of the plate 23 to jamming position locks the tool 30 to the closure, and the positions of the elements of the closure and the tool head 30 are shown in Figures 4, 5 and 6.

As the rotation of the tool to detach the closure from the fill box continues, the plate 23 rotates in unison with the plug or closure member to rotate the latter with respect to the upper threaded section of the threaded cylinder 11 of the unit until the plug or closure member is detached and removed from the unit. The tool remains locked to the plug or closure member and the positions of the tool head 30 and the elements are still in the same interlocking relationship shown in Figures 4, 5 and 6. The operator cannot readily separate the tool from the closure when the closure is uncoupled from the unit and because of this they are maintained to-

gether when the closure is detached from the unit.

When it is desired to couple the detached plug or closure member to the unit, the operator grasps the handle 33 of the tool and carries the closure, which is interlocked therewith, to the unit to couple the same thereto. The coupling 20 of the closure is placed adjacent the coupling 11 of the unit and the tool is counter rotated. During counter rotation of the tool, the tool head 30 in locked relationship to the closure rotates the closure so that the plug 20 is screwed down into the female coupling 11 of the unit until the gasket 22 is firmly pressed between the lower face of the flange 21 and the seating face 13 of the cylinder 11 of the unit. During this entire counter rotation of the tool and plug or closure member 20, the tool remains locked to the closure, as shown in Figures 4, 5 and 6. After the closure forms a tight seal with the fill box unit, upon further counter rotation of the tool, the tool head 30 rotates the socket plate 23 and said plate 23 travels downwardly until it is stopped against the stop pin 24 when the openings in socket plate 23 and cover plate 27 are in register so that the tool may be removed therefrom.

Thus, since the socket plate 23 remains in its upper position and with the tool locked to the closure until after the closure has been tightly coupled to the unit, a tight coupling is assured because the workman cannot remove the tool until after a tight seal has been made.

Although the invention has been described in detail, it is not to be limited to the exact construction as shown because various modifications may be made within the spirit of this invention.

What is claimed:

1. In combination a removable closure plug for a fill box or like access opening and a wrench tool therefor, said closure plug having means operative by rotation thereof for connecting the same in closed relation to the opening served thereby, said closure plug having an internally screw threaded recess in the top thereof, a socket plate having a non-circular wrench head receiving socket, said socket plate being threaded into said recess subject to combined rotary and vertical movement therein, a cover plate affixed to said closure plug and over said recess, said cover plate having a non-circular wrench head passage with which said receiving socket registers when said socket plate occupies a down turned normal initial position, said wrench tool having a conforming head to pass through said cover plate passage to fitted relation within said receiving socket of said socket plate, and said socket plate by rotation of said wrench head being turnable into jammed connection with said cover plate whereby rotary motion may be imparted to said closure plug after portions of said wrench head are moved out of register with said non-circular cover plate passage and beneath said cover plate to interlock said wrench tool and closure plug together.

2. In combination a removable closure plug for a fill box or like access opening and a wrench tool therefor, said closure plug having means operative by rotation thereof for connecting the same in closed relation to the opening served thereby, said closure plug having an internally screw threaded recess in the top thereof, a socket plate having a non-circular wrench head receiving socket, said socket plate being threaded into said recess subject to combined rotary and

vertical movement therein, a cover plate affixed to said closure plug and over said recess, said cover plate having a like non-circular wrench head passage conformable to and with which said receiving socket registers when said socket plate occupies a down turned normal initial position, stop means to determine the normal initial down turned position of said socket plate, said wrench tool having a conforming head to pass through said cover plate passage to fitted relation within said receiving socket of said socket plate, and said socket plate by rotation of said wrench head being turnable into jammed connection with said cover plate whereby rotary motion may be imparted to said closure plug after portions of said wrench head are moved out of register with said cover plate passage and

beneath said cover plate to interlock said wrench tool and closure plug together.

3. In the combination of removable closure plug and wrench tool as defined in claim 1, wherein margins of said cover plate passage and margins of said wrench head are provided with cooperating chamfered lips operative to outwardly eject said wrench head from said cover plate passage if inserted therein and turned. 5

4. In the combination of removable closure plug and wrench tool as defined in claim 2, wherein margins of said cover plate passage and margins of said wrench head are provided with cooperating chamfered lips operative to outwardly eject said wrench head from said cover 10 plate passage if inserted therein and turned. 15
